UNITED STATES PATENT OFFICE.

ADELBERT CARPENTER, OF MINNEAPOLIS, MINNESOTA, ASSIGNOR TO THE MONITOR MANUFACTURING COMPANY, OF SAME PLACE.

GRAIN-DRILL.

SPECIFICATION forming part of Letters Patent No. 520,843, dated June 5, 1894.

Application filed March 3, 1894. Serial No. 502,198. (No model.)

To all whom it may concern:

Be it known that I, ADELBERT CARPENTER, residing at Minneapolis, in the county of Hennepin and State of Minnesota, have invented 5 certain new and useful Improvements in Grain-Drills; and I do hereby declare the following to be a full, clear, and exact description of the invention, such as will enable others skilled in the art to which it appertains to make and use the same.

My invention relates to an improvement in grain drills, and more particularly to press-ure devices for the shoes or hoes and the covering or press wheels,—the object of the in- 15 vention being to produce simple and efficient means whereby pressure can be applied in- dependently upon the shoes or hoes and the covering or press wheels.

With this object in view, the invention 20 consists in certain novel features of construction and combinations and arrangements of parts as hereinafter set forth and pointed out in the claims.

In the accompanying drawings: Figure 1 is 25 an elevation of a grain drill illustrating my improvements applied thereto. Figs. 2, 3 and 4 are enlarged detail views of the pressure devices.

A represents the frame of a grain drill hav- 30 ing an axle *a* mounted thereon for the accom- modation of the carrying wheels *a'*, said axle preferably passing through a portion of the bracket *a* which supports the hopper *a*. The drill shoes or hoes *B* (each being prefer- 35 ably provided with a boot *B'* for the recep- tion of the feed tubes from the hopper), are located in the usual position below the hopper and are connected with the forward end of the frame by means of suitable pull bars *b*.

40 At the rear end of the frame *A*, a shaft *C* is mounted and provided with rearwardly pro- jecting arms *C'*, which latter are connected with the pressure devices hereinafter fully de- 45 scribed. The shaft *C* is also provided with a toothed segment *c* adapted to mesh with and receive motion from a toothed segment *c'* car- ried by a short shaft *c* mounted above the shaft *C*. The shaft *c* also has a lever *D* se- 50 cured thereto, said lever being provided with a handle *d* and a latch bar *d'* adapted to en- gage a segment *d* made rigid with the bracket

which supports the hopper and said latch bar is operated by means of a finger bar *d* connected with the latch bar by spring actuated rods *d*. By operating the lever *D* motion 55 will be transmitted to the shaft *C* through the medium of the gearing above described and said shaft *C* being turned, the arm *C'* will be raised or lowered, thus serving to raise or lower the shoe or hoe and the press wheel in 60 a manner which will be hereinafter made ap- parent. Each press wheel *E* will be mounted in bars *e*, the forward ends of which will em- brace the boots *B'* and are pivotally connected to a lug *f* projecting forwardly from each boot. 65 The lug *f* of each boot will preferably be made with a series of perforations *f*, whereby to lighten the casting. At the rear end of the bars *e*, a scraper *f* is attached and adapted to re- move earth adhering to the press wheel. Be- 70 low the bars *e* lugs *g* project laterally from the boot *B'*. A rod *F* is connected at its lower end to a lug *h* projecting rearwardly from the boot *B'*, one of said rods being thus attached to each boot. The upper end of the rod *F* passes 75 loosely through a collar *i* having trunnions *i*, mounted in the bifurcated free end of the arm *C'*. A spring *G* encircles the rod *F*, one end of said spring bearing on a disk or washer *j* located on the lugs *h* and the other end bear- 80 ing on the collar *i* at the upper end of said rod *F*. By means of this spring the proper pressure is maintained on the shoe or hoe. A bracket *H* is made tubular at its upper end, as at *k*, and the downwardly projecting arms *k* of said bracket are provided at their lower 85 extremities with laterally projecting lugs or pins *l* adapted to enter perforations in the bars *e* which carry the press wheel. The bars *e* will each be provided with a series of per- 90 forations *m* so that the attachment of the bracket *H* thereto can be adjusted as desired. The rod *F* and spring *G* are adapted to pass loosely through the tubular portion of the bracket *H*, and also passing loosely through 95 said tubular portion of the bracket is a tubu- lar casting *I*, preferably slotted to secure lightness. The upper end of the tubular portion of the bracket is recessed to produce a seat *n* for the lower end of a spring *J* which 100 encircles said tubular casting, the upper end of said spring being adapted to bear against

- a flange *o* at the upper end of the tubular casting *I*,—said spring thus supplying the necessary pressure on the press wheel. It is of course to be understood that the pressure devices above described are provided for each shoe or hoe and press wheel. If desired the tubular casting *I* may be dispensed with and the springs *G* and *J* located one within the other. When it is desired to raise the shoes or hoes and press wheels, the lever *D* will be operated to raise the free ends of the arms *C'*, whereupon the rods *F* will be raised, thus raising the shoes or hoes, and the lugs *g*, beneath the arms *e* will engage said arms and thus the press wheels will be raised simultaneously with the shoes or hoes and by the operation of the same lever.
- From the construction and arrangement of parts above described it will be seen that the necessary pressure will be applied to the shoes or hoes and the press wheels and that the pressure applied to the shoes or hoes will be entirely independent of the pressure applied to the press wheels, so that the yielding action of one does not depend in any manner upon the yielding action of the other. By arranging the castings *H* and *I* telescopically, the pressure devices are made compact in form.
- My improvements are very simple in construction, comparatively cheap to manufacture, easy of application and effectual, in every respect, in the performance of their functions.
- Various slight changes might be made in the details of construction of my invention without departing from the spirit thereof or limiting its scope and hence I do not wish to limit myself to the precise details of construction herein set forth but,
- Having fully described my invention, what I claim as new, and desire to secure by Letters Patent, is—
1. The combination with the shoe or hoe and the press or covering wheel of a grain drill, of a spring adapted to apply pressure on said shoe or hoe, and a spring adapted to independently apply pressure to said press or covering wheel, said spring being arranged one within the other, substantially as set forth.
  2. In a grain drill, the combination with a rearwardly projecting arm, a shoe or hoe, bars or brackets connected to said shoe or hoe and a press wheel carried by said bars or brackets, of a rod connected at one end with the shoe or hoe and at the other end with said rearwardly extending arm, a spring encircling said rod, and bearing at its respective ends against the connection of said rod to the rear-

wardly extending arm and the shoe or hoe, and a spring encircling said first mentioned spring and adapted to exert pressure on the press wheel, substantially as set forth.

3. In a grain drill, the combination with a rearwardly extending arm, a shoe or hoe, bars or brackets connected to the shoe or hoe and a press wheel mounted in said arms or brackets, of a collar mounted in the free end of said rearwardly extending arm, a rod passing loosely through said collar at one end and at its other end connected with said shoe or hoe, a spring encircling said rod and bearing at its respective ends against said collar and the connection of said rod with the shoe or hoe, and a spring encircling the first-mentioned spring and exerting pressure on said bars or brackets in which the press wheel is mounted, substantially as set forth.

4. In a grain drill, the combination with a shoe or hoe, bars connected thereto, a press wheel mounted in said bars, and a rearwardly extending arm, of a rod connected at its ends to said arm and the shoe or hoe, a spring encircling said rod and bearing at its respective ends on the connection of said rod to the rearwardly extending arm and the shoe or hoe, a bracket through which said spring loosely passes, said bracket being pivotally connected to the bars in which the press wheel is mounted, a tubular casting encircling said spring and adapted to pass loosely through the upper end of said bracket and provided at its upper end with a flange or shoulder, and a spring encircling said tubular casting and bearing at its respective ends on the bracket and said flange or shoulder, substantially as set forth.

5. In a grain drill, the combination with a rearwardly extending arm, a shoe or hoe, bars connected to said shoe or hoe and a press wheel mounted in said bars, of a rod connected with said shoe or hoe and said rearwardly extending arm, a spring encircling said rod and adapted to exert pressure on said shoe or hoe, a bracket through which said spring loosely passes, means for adjustably connecting said bracket to said bars in which the press wheel is mounted and a spring bearing on said bracket, substantially as set forth.

In testimony whereof I have signed this specification in the presence of two subscribing witnesses.

ADELBERT CARPENTER.
